(57) **CLAIM**

The ornamental design for automobile headlight lens, as shown and described.

DESCRIPTION

FIG. 1 is a frontal perspective view of a right automobile headlight lens attached to a vehicle, no part of the vehicle is claimed;

FIG. 2 is a perspective view of the right automobile headlight lens;

FIG. 3 is a front elevation view of the right automobile headlight lens;

FIG. 4 is a right side view of the right automobile headlight lens;

FIG. 5 is a top plan view of the right automobile headlight lens;

FIG. 6 is a bottom plan view of the right automobile headlight lens;

FIG. 7 is a frontal perspective view of an alternative embodiment of the automobile headlight lens illustrated in FIGS. 1-6, showing a left automobile headlight lens attached to a vehicle, no part of the vehicle is claimed;

FIG. 8 is a perspective view of the left automobile headlight lens;

FIG. 9 is a front elevation view of the left automobile headlight lens;

FIG. 10 is a left side view of the left automobile headlight lens;

FIG. 11 is a top plan view of the left automobile headlight lens; and,

FIG. 12 is a bottom plan view of the left automobile headlight lens.

The phantom lines are not a part of the claimed invention. The stippling indicates the curvature of the automobile headlight lens.
